SELF-CLEANING SWITCH

Filed Dec. 16, 1940

Fig. 1

UNITED STATES PATENT OFFICE

2,310,595

SELF-CLEANING SWITCH

Charles S. Packer, Chicago, Ill., assignor to Just-
rite Manufacturing Company, Chicago, Ill., a
corporation of Illinois

Application December 16, 1940, Serial No. 370,293

1 Claim. (Cl. 200—60)

The invention relates to electrical switches and has more particular reference to a self-cleaning switch for flash lights, battery signal lights, and other electrical apparatus of this general nature.

An object of the present invention is to provide improved switch structure which will be self-cleaning so that the contacts will make good electrical connection at all times.

Another object is to provide a switch having a reciprocating switch contact constructed and arranged so that the contact may also be rotated, whereby a wiping action is produced as a result of said rotation to maintain the contacts clean for making a good electrical connection.

With these and various other objects in view, the invention may consist of certain novel features of construction and operation, as will be more fully described and particularly pointed out in the specification, drawing and claim appended hereto.

In the drawing which illustrates an embodiment of the device and wherein like reference characters are used to designate like parts—

Figure 1 is a top plan view of a cap member for a lamp casing or the like having the switch of the invention applied thereto;

Figure 2 is a bottom plan view showing in detail the structure of the switch;

Figure 3 is a sectional view taken along line 3—3 of Figure 1 showing the switch in "off" position;

Figure 4 is a sectional view similar to Figure 3 but showing the switch in "on" position; and

Figure 5 is a sectional view taken substantially along line 5—5 of Figure 1.

Referring to the drawing, the switch structure of the invention is shown in associated relation with a cap member 10 for a lamp casing such as a battery signal light or other similar apparatus. The said cap member is substantially rectangular in form and includes a substantially flat top portion 11 provided with a stepped periphery 12 and a depending flange 13. In Figure 2 the switch structure is shown in supported relation with respect to the top portion 11, the same having suitably secured thereto the rivets 14, which, as shown in Figure 3, receive a spacing member 15 to support an insulating disc 16 in spaced relation with the top 11. Both ends of the rivets 14 are similarly shaped, one end being beaded over the top 11, whereas, the opposite end is beaded over the insulating disc 16. The disc supports a metal ring 17 of brass, copper or other suitable conducting material which forms one

terminal of the battery circuit or other electrical circuit to be controlled by the switch structure of the invention. The rivets 18 suitably secure ring 17 to the underside of the insulating disc 16 and as shown in Figure 2, three rivets may be employed, with one of the rivets additionally securing to the disc a terminal member 20. Said terminal member is provided with the opening 21 whereby the same may be connected with a wire or the like, and the rivet 18 secures said terminal member to the insulating disc 16 on the upper side thereof opposite the ring 17. Said rivet in addition forms conducting means electrically connecting terminal member 20 with said ring.

The central terminal 22, which forms the other terminal of the battery circuit or other electrical circuit, is secured to the disc 16 by the central rivet 23. It will be understood that disc 22 is substantially concentric with ring 17. The rivet 23 additionally secures to the disc a switch terminal 24 in a similar position but on the opposite side of the insulating disc 16. Said terminal 24 may be of copper or brass, or any other suitable metal for conducting electricity. Terminal 24 provides one contact for the switch, the other being provided by the strip 25 of metal or other suitable material which is secured to the insulating disc 16 by one or more rivets such as 26. The strip 25 is disposed in spaced relation with respect to the central contact 24 and one end of the same overhangs the insulating disc to provide a terminal end having an opening 27 for receiving an electrical wire whereby connection may be made to contact 25 in much the same manner as terminal 20 has an opening for receiving a wire so that an electrical connection may be made with ring 17.

The invention provides a reciprocating switch contact indicated in its entirety by numeral 28 which in addition to having reciprocating movement for making and breaking an electrical circuit also may have rotation in order that the contacting surface may be kept clean. Said movable contact 28 includes a circular member having a substantially flat top on which is disposed an insulating disc 29. The under side of the member is provided with diagonal surfaces 30 extending completely around the circumference of the member. The extreme bottom of the member is flat, providing a flat contact surface 31, Figure 5, and centrally thereof the same is recessed as at 32 to receive the base end of the actuating stud 33. On its upper end said stud is provided with the knurled finger portion or knob

34, which portion has movement within the slot 35 in the top 11 when reciprocating movement is imparted to the movable contact 28. The slot 35 controls movement of the switch contact 28 so that when moved in one direction the switch contact will bridge the gap between the terminals 24 and 25 thereby electrically connecting the terminals. Movement of the switch contact in an opposite direction will of course open the gap to electrically disconnect the terminals.

It is necessary to yieldingly maintain the movable contact member 28 in engagement with the switch contacts 24 and 25 and for this purpose the stud 33 retains a coil spring 36 confined between the insulating disc 29 and a similar insulating member 37. The coil spring is thus retained under tension and since the insulating member 37 is in contact with the top portion 11 the action of the spring is to maintain the movable contact 28 against switch contact 25 when in "off" position and against both switch contacts 24 and 25 when in "on" position. An important feature of the invention resides in the provision of stops in the form of projections 40 and 41 which are suitably secured in spaced relation to the contact strip 25. The said projections are designed to coact with the diagonal surfaces 30 to provide stop means for holding the movable switch contact in either an "on" or an "off" position of the switch, as shown in Figure 3, projection 40 is effective to prevent inadvertent movement of the switch contact 28 in a direction toward the left. It is necessary for the switch contact to move in this direction to assume an "on" position and accordingly positive pressure must be exerted by the operator on the knurled finger portion of knob 34 to cause the switch contact to move up over the projection 40 and into a position as shown in Figure 4. In Figure 4 the circuit from contact 25 to contact 24 is closed and the switch accordingly is in "on" position. The projection 41 in this case constitutes a stop effectively preventing inadvertent movement of the switch contact toward the right in a direction to discontinue the electrical connection. However, when adequate pressure is applied to the knob 34 contact 28 will move up over projection 41 and the same therefore requires a positive act of the operator to open the electrical circuit.

Movement of the switch contact 28 over the projections 40 and 41 was rendered possible by the resilient support of the said switch contact which permits movement of the same upwardly against the tension of the coil spring 36. This mounting of the switch contact also makes possible rotary movement of the same and since this movable contact is circular, having diagonal surfaces 30 extending around its circumference the particular rotative position of the same is immaterial.

With the cap member in place on its lamp casing the ring 17 is designed to make contact with one terminal of a battery such as a dry

cell retained within the lamp casing. The central pole of the battery will contact the central disc 22. The circuit is completed to the light by the wires connecting with the members

5 20 and 25. It will be observed that the circuit is made or broken by the movable switch contact 28 which is reciprocable, being guided by the slot 35 from an "off" position to an "on" position and vice versa. As a result of the projections 10 40 and 41 providing stops in the path of the movable switch contact 28 the same is releasably held in either of its two positions.

An improved feature of the invention resides in the provision of a rotatable switch contact 15 which, by reason of its rotation, produces a wiping action to maintain the contacts clean and provide for a good electrical connection at all times. The knob 34 may be knurled to facilitate rotation of the member 28 and which may 20 take place automatically as the member is reciprocated, or which may be rotated by a positive act of the operator. In either position the member is yieldingly held in engagement with one or both of the contacts 24 and 25 and said 25 rotation will produce a wiping action on said contacts and a wiping action with respect to the flat bottom surface 31 of the member.

The invention is not to be limited to or by 30 details of construction of the particular embodiment thereof illustrated by the drawing, as various other forms of the device will of course be apparent to those skilled in the art without departing from the spirit of the invention or 35 the scope of the claim.

What is claimed is:

In a switch, the combination with a cap member for a lamp casing, of an insulating disc secured in spaced relation to the interior surface of the cap member, contact elements secured to the inner surface of the disc adjacent the cap member including a central terminal and a peripheral terminal in spaced relation, a movable switch contact of circular shape normally in engagement with the peripheral terminal, said 40 switch contact having a diameter greater than the space between the central and peripheral terminals so that the switch contact may bridge the gap when moved to engage both said terminals, said cap member having a slot therein and 45 the switch contact having a rigid handle portion extending through the slot whereby the switch contact is guided for movement to and from a gap closing position to electrically connect or disconnect the terminals, a plate carried by said 50 handle portion and positioned in contact with the inner surface of the cap member to close the slot, resilient means encircling the handle portion and confined between the plate and the switch contact for yieldingly biasing the switch 55 contact in a direction toward the insulating disc, and means provided by the peripheral terminal for releasably maintaining the movable switch contact in either of its two positions.

CHARLES S. PACKER.

CERTIFICATE OF CORRECTION.

Patent No. 2,310,595.

February 9, 1943.

CHARLES S. PACKER.

It is hereby certified that error appears in the printed specification of the above numbered patent requiring correction as follows: Page 2, first column, line 30, for "an 'off' position of the switch, as shown in Fig--" read --an "off" position. In the "off" position of the switch, as shown in Fig--; and that the said Letters Patent should be read with this correction therein that the same may conform to the record of the case in the Patent Office.

Signed and sealed this 20th day of April, A. D. 1943.

Henry Van Arsdale,

(Seal)

Acting Commissioner of Patents.
